member 67 constitutes a handle by which the stud 77 may be disengaged from the recess 73, so that the member 67 may be swung longitudinally of the slot 72, and thereby 5 change the adjusted position of the stop member 68'. Adjacent to the lower corner of the shifting plate 28 is a forwardly extending stud 79, adapted to impinge upon the top of the member 68, for shifting the 10 plate 28 from the position shown, to its other alternative position, in which the stud 30 will rest in the opposite end of the arcuate slot 29, and the stud 34 will then be on the opposite side of the carriage 24 from 15 its present position.

A setting lever 80 is pivoted at 81 to the base plate 10, and is provided with a stud 82, adapted to impinge upon the edge 28' of the plate 28, when the lower arm of the 20 lever 80 is swung laterally. In order to swing the lever 80, a pull rod 83 is pivotally connected at 84 to the upper arm of the lever 80, and the rod 83 is extended downward and terminates in a forwardly extending 25 finger piece or handle 83', which extends through a slot 85, in the base plate. The lever 80 is pivotally connected at 86 with a spring 87, secured to the guide member 39, and by means of this spring, the lever 80 30 and pull rod 83 are returned to their normal positions, as shown; the rod 83 acting as a stop for the stud 82.

In operation, the operator pulls the carriage 24 downward, by means of the strip 38, as described, thereby drawing the catch 41 downward; and, said catch being in engagement with the arm 42^a of the left-hand bar 42 (see Fig. 2), this bar 42 is pulled downward so as to swing the bell crank 44 40 to which it is connected by one of the links 43, so that the other link 43, which is attached to the opposite arm of this bell crank and to the adjacent slide bar 42, draws this adjacent slide bar upward while 45 the beam 25 goes downward, until the arm 42^a of the upwardly moving slide bar is on a higher plane than the upper end of the beam 25, and the stud 40 clears the lower end of the adjacent tongue 65, so that the beam 25 50 is drawn laterally, by means of the plate 28, link 33 and spring 32; so that the stud 40 now registers with the next succeeding slot 64, the movement of the beam 25 having been arrested in this position by means of 55 the arm 42^a of the contiguous bar 42 upon which it has impinged. Now, as the bell crank 44 was swung on its pivot, by the operation just described, the upper link 55 caused the upper jointed lever to swing on 60 its pivot 57, thereby swinging the arm 58, together with its clamp 63 and the music leaf clamped thereby, through an angle of one hundred and eighty degrees. It will be noted that the member 53 is swung through 65 a considerably less angle than one hundred

and eighty degrees, but the swing of the member 52 and arm 58 is increased by means of the leverage gained by the pivotal connection at 54 and the stud and slot connection at 51 and 52^x (see Fig. 4). Referring 70 to the preceding operations, wherein the stud 40 is in registry with the second slot, it will be seen that upon allowing the carriage 24 to ascend, the stud 40 will move up into this second slot, and the catch 41 will engage with the arm 42^a of the third slide bar 42; so that when the carriage 24 and its adjuncts are again lowered, this third bar 42 will be engaged by the catch 41, so as to 75 rock the bell crank 45 to which it is connected; thereby actuating the second jointed lever and turning the second music leaf, in the same manner that the first music leaf was turned. This operation continues until 80 all of the slots 64 have been entered by the stud 40 and until all of the leaves have been turned, in which operation all of the bars 42 have been moved and all of the bell cranks have been swung on their pivots; provided that there are just four music 85 leaves to be turned. It will be seen that as the upper end of the beam 25 swings rightward (see Fig. 2), its lower end swings leftward, thereby drawing the lower end of the plate 28 and its stud 79 leftward; so that, 90 at this stage, when the carriage 24 is again drawn downward, the stud 79 will be arrested by the upper end of the stop 68, and the plate 28 is thereby swung leftward on its pivot 27 until the stud 30 rests in the 95 right-hand end of the slot 29. In swinging leftward, the plate 28 carries the rod 33 leftward beyond the pivot 27, so that the upper end of the beam 25 tends to move leftward, so that when the stud 40 is released from the right-hand slot 64, it moves 100 into registry with the second slot 64 to the left, and is there arrested by the bar 42 immediately to the left thereof, having impinged upon the arm 42^a of said bar. During 105 this rightward movement, the beam 25 and its adjuncts have pulled each alternate, slide bar 42 downward, and thereby caused the other alternate slide bars to move upward, and now, in this return movement of 110 the beam 25 and its adjuncts, the bars that were formerly moved upward are now pulled downward, so that the bell-cranks 44 and 45 are moved in the opposite direction, so as to swing the jointed levers, the arms 38 and the music sheets in the opposite direction; so that by several rapid oscillations of the carriage 24 the leaves are 115 quickly returned to their normal position, in case it is desired to play the music over again.

In order that the music may be properly supported, I provide a shelf 88, preferably composed of two similar halves, which are 120 provided with apertured ears 89, and 130

UNITED STATES PATENT OFFICE.

WILLIAM H. ARNOLD, OF MORNING SUN, IOWA.

LOCKING DEVICE FOR LADDERS.

1,125,251.

Specification of Letters Patent.

Patented Jan. 19, 1915.

Application filed August 3, 1914. Serial No. 854,840.

To all whom it may concern:

Be it known that I, WILLIAM H. ARNOLD, a citizen of the United States, residing at Morning Sun, in the county of Louisa and State of Iowa, have invented certain new and useful Improvements in Locking Devices for Ladders, of which the following is a specification, reference being had to the accompanying drawings.

10 This invention relates to ladders and more particularly to an improved locking device which has for its primary object to provide simple, reliable and efficient means for locking the support which is pivoted to the ladder proper and thereby preventing the collapse of the ladder in the use of the same.

15 In its more specific aspect, the invention embodies in its preferred form a substantially U-shaped locking rod having its intermediate portion pivotally mounted upon the upper end of the ladder proper adjacent to the pivot of the ladder support, plates pivotally mounted at one of their 20 ends upon the side bars of said support, the extremities of the locking rod being outwardly turned and loosely disposed through the other ends of said plates for engagement with the edges of the side bars of the ladder support, whereby the pivotal or spreading movement of said support with respect to the ladder proper is limited.

25 The invention has for a further object to provide a locking device for ladders of the above character which may be readily applied to ladders of ordinary construction now in general use, and will admit of the folding of the support with respect to the ladder proper without necessitating the 30 manipulation of the lock in order to release said support for folding movement.

35 With the above and other objects in view as will become apparent as the description proceeds, the invention consists in certain 40 constructions, combinations and arrangements of the parts that I shall hereinafter fully describe and claim.

45 For a full understanding of the invention, reference is to be had to the following 50 description and accompanying drawing, in which—

Figure 1 is a perspective view of a ladder having my improved locking attachment applied thereto; Fig. 2 is a side elevation, 55 the ladder being folded; Fig. 3 is a section

taken on the line 3—3 of Fig. 2; and Fig. 4 is a section taken on the line 4—4 of Fig. 2.

Referring in detail to the drawing wherein I have illustrated a very well known construction of step ladder, 5 designates the ladder proper, and 6 the supporting section therefor. The longitudinal side bars 7 of the ladder section and the corresponding bars 8 of the support preferably converge slightly from their lower to their upper 60 ends, the bars of the ladder section being disposed between the side bars of the support at the upper end of the latter and projecting above the same. The support 6 is connected to the ladder proper by means of 65 the pivot bolts 9 so that the ladder 5 may be folded with respect to its support and disposed between the side bars 8 thereof, as shown in Fig. 2. The bars 8 are connected adjacent to their lower ends by means of the 70 brace bar 10.

In the use of the ladder, the support 6 and the ladder 5 are moved in opposite directions or separated in the usual manner so that the ladder proper will be supported 80 in an inclined position. In order to limit this spreading movement of the ladder and its support and obviate collapse of the same, I provide my improved locking device which consists in a U-shaped metal rod 11 85 of requisite diameter, the intermediate portion of which is pivotally mounted in the eyes 12 fixed in the rear edges of the side bars 7 of the ladder at a point slightly above the pivot bolts 9. The side arms of this U-shaped rod extend in parallel relation to the side bars 8 of the support 6 and have their extremities angularly bent and outwardly extended, as indicated at 13. Metal plates 14 are pivoted at one of their ends, as 90 shown at 15, upon the inner faces of the bars 8 while the other ends of these plates are provided with openings to loosely receive the out-turned ends 13 of the rod 11. These extremities of the locking rod extend 95 across the rear edges of the bars 8 and are adapted for bearing engagement thereon when the support is separated from the ladder proper, as shown in Fig. 1. It will thus be obvious that the opening or spreading movement of the ladder and its support is limited and the support securely locked against a further outward pivotal movement whereby the complete collapse of the ladder, under a weight imposed thereon, is 100 105 110
